(57) CLAIM

The ornamental design for a skirt, as shown and described.

DESCRIPTION

FIG. 1 is a perspective view of a skirt showing my new design;

FIG. 2 is a top plan view thereof;

FIG. 3 is a front elevational view thereof;

FIG. 4 is left side elevational view thereof;

FIG. 5 is a right side elevational view thereof; and,

FIG. 6 is a rear elevational view thereof.

The broken line showing of portions of the human form, in FIGS. 1-6, forms no part of the claimed design.
